(57) **ABSTRACT**

A button system containing two pieces that snap and lock together to fasten multiple articles of clothing. The top piece is made of three distinct parts: a detachable ridged color-coded cover, a fastener that attaches said cover to a rotatable hinged plate, and a fastener that secures all three pieces of the top piece. The bottom piece is also made up of three distinct parts: a plate to receive the hinges from the top piece, a curved structure that connects the hinge/cavity plates to the article of clothing, and a rivet that attaches to the article of clothing and the snap and lock invention.

SNAP AND LOCK

BACKGROUND

Field of the Invention

This invention relates to the field of buttons, specifically fasteners for articles of clothing.

Description of the Related Art

Traditional buttons have long been used to easily fasten multiple articles of clothing together. A negative trait of the ease of traditional buttons is the ease at which they become undone. The present invention sets forth a novel system to allow the user to rotate the fastening device into a locked position to secure multiple articles of clothing and prevent unwanted detachment of said articles of clothing. This invention is particularly useful in athletics, action sports, and extreme conditions.

SUMMARY

The snap and lock invention is similar to a traditional button designed for an article of clothing, generally two pieces that snap together to fasten multiple articles of clothing.

This invention comprises the traditional two pieces, however, each piece incorporates novel concepts. The top piece is made up of two parts: (1) a ridged cover that is used as both a pressure point to secure the invention, and a grip to rotate the invention in and out of the locked position, and a male fastener that attaches the ridged cover to the (2) plate with hinges that functions as the bottom of the top piece of the snap and lock: The hinged plate contains a female fastener that secures the two pieces of the top portion. The bottom piece of the snap and lock invention is made up of three parts: (1) a plate to receive the hinges from the top piece, said plate either closed or open, with a cavity to allow the hinges to rotate approximately 37 degrees into a locked position, and with bumper guards to prevent the hinges from over rotation, (2) a curved structure that serves to connect the hinge/cavity plates and the article of clothing attachment, and (3) a rivet that attaches to the article of clothing and the snap and lock invention. The invention also includes a member device that holds the invention together and guides the installation or assembly.

BRIEF DESCRIPTION OF THE DRAWINGS

The foregoing and other features of the invention will become apparent from the following drawings and detailed description of the preferred embodiment of the invention:

FIG. 1 is a front schematic view of the snap and lock button device open design;

FIG. 2 is a cross-sectional view of the device shown in FIG. 1 taken from the center of the device;

FIG. 3A is a semi-explored angled view of the device shown in FIG. 1;

FIG. 3B is a semi-explored front view of the device shown in FIG. 1;

FIG. 3C is a semi-explored front-angled view of the device shown in FIG. 1;

FIG. 4 is a front schematic view of the snap and lock button device closed design;

FIG. 5 is a cross-sectional view of the device shown in FIG. 4 taken from the center of the device;

2

FIG. 6A is a semi-explored angled view of the device shown in FIG. 4;

FIG. 6B is a semi-explored front view of the device shown in FIG. 4;

FIG. 6C is a semi-explored front-angled view of the device shown in FIG. 4;

FIG. 7 is a front schematic view of the snap and lock button installation device;

FIG. 8 is a cross-sectional view of the device shown in FIG. 7 taken from the center of the device with the open design;

FIG. 9 is a semi-explored front-angled view of the device shown in FIG. 7 with the open design;

FIG. 10 is a cross-sectional view of the device shown in FIG. 7 taken from the center of the device with the closed design; and

FIG. 11 is a semi-explored front-angled view of the device shown in FIG. 7 with the closed design.

20

DETAILED DESCRIPTION

FIG. 1 is a front schematic view of the invention in the preferred embodiment with the open design. The preferred embodiment is not intended to limit the scope of the invention. The preferred embodiment of the invention includes five parts: the ridged top plate 10 containing the star-shaped open clasp male fastener 11, the plate 20 containing the star-shaped open clasp female fastener 22 which connects to plate 10 and also contains hinges 21 on the reverse side of the female fastener, the plate 30 that receives the hinges 21 in cavities 31, a structure 40 that receives the plate 10 and plate 20 and allows the combined plates 10 and 20 to be rotated together into a fixed and secure position, and a rivet 50 that attaches the invention to an article of clothing.

FIG. 2 shows the cross-sectional view of the invention taken from the center of the invention. The ridged top plate 10 is shown attached to plate 20 with fastener 11 inserted to fastener 22 by snapping in place with applied downward force. Plate 20 with hinges 21 is locked in place with plate 30 with hinges 21 inside cavities 31 with said hinges inserted in said cavities and rotated approximately 37 degrees into a locked position. Bumper guides 32 guide hinges 21 into cavities 31 into a locked position keeping them from moving into the text cavity. Plate 20 is shown connected into structure 40 by snapping in place with applied downward force. Rivet 50 is shown detached from the invention and from an article of clothing.

FIG. 3A is a semi-explored view of the invention in the preferred embodiment. The ridged top plate 10 containing the star-shaped open clasp male fastener 11 is shown separated from plate 20. The plate 20 containing the star-shaped open clasp female fastener 22 and hinges 21 is shown detached from the plate 10 containing the male fastener. The plate 20 containing the female fastener and hinges 21 is shown detached from the plate 30 that receives the hinges 21 inside cavities 31 with bumper guides 32.

This FIG. 3A shows the open design for plate 30. Structure 40 that receives the united plate 10 and plate 20 is shown detached. Rivet 50 is shown detached from the invention and from an article of clothing.

FIG. 3B is a semi-explored front view of the invention in the preferred embodiment and while incorporating the detailed description of FIG. 3A above, also shows fastener 11 and fastener 22.

FIG. 3C is a semi-explored front-angled view of the invention in the preferred embodiment and while incorporating the detailed description of FIG. 3A above.

FIG. 4 is a front schematic view of the invention in the preferred embodiment with the closed design for plate 30, and incorporates the detailed description of FIG. 1.

FIG. 5 shows the cross-sectional view of the invention taken from the center of the invention with the closed design for plate 30, and incorporates the detailed description of FIG. 2 above.

FIG. 6A is a semi-explored view of the invention with the closed design for plate 30, and incorporates the detailed description of FIG. 3A above.

FIG. 6B is a semi-explored front view of the invention with the closed design for plate 30, and incorporates the detailed description of FIG. 3B above.

FIG. 6C is a semi-explored front-angled view of the invention with the closed design for plate 30, and incorporates the detailed description of FIG. 3C above.

FIG. 7 is a front-angled view of the plate 20 enclosed in installation device 60, said installation device holds the invention in place and guides installation and assembly of the invention.

FIG. 8 shows the cross-sectional view of the installation device 60 operating on the invention taken from the center of said device. In this FIG. 8, plate 30 is in the open design. The detailed description of FIG. 2 above is incorporated herein this FIG. 8.

FIG. 9 is a semi-explored front-angled view of the installation device 60 operating on the invention while incorporating the detailed description of FIG. 3A above. In this FIG. 9, plate 30 is in the open design. Plate 10 is not shown in this FIG. 9.

FIG. 10 shows the cross-sectional view of the installation device 60 operating on the invention taken from the center of said device. In this FIG. 10, plate 30 is in the closed design. The detailed description of FIG. 2 above is incorporated herein this FIG. 10.

FIG. 11 is a semi-explored front-angled view of the installation device 60 operating on the invention while incorporating the detailed description of FIG. 3A above. In this FIG. 11, plate 30 is in the closed design. Plate 10 is not shown in this FIG. 11.

What is claimed is:

1. A button system for an article of clothing or any item requiring fastening, said button system comprising: a top member and bottom member capable of incorporation into an article of clothing;

said top member consisting of a detachable, rotatable, and interchangeable ridged cover that is used as both a pressure point to secure said top member to said bottom member, a male fastener that attaches to said ridged cover, and a plate with L-shaped hinges and a female fastener to secure all components of the top member; said bottom member consisting of a plate to receive said hinges from said top member, said plate with a cavity to allow the hinges to rotate counterclockwise 37 to 42 degrees into a locked position, and said plate with bumper guards to prevent the hinges from over rotation, and a rivet to attach to the article of clothing to the invention.
